CLAIM

What is claimed is the ornamental design for a multi-tool for fasteners, as shown and described.

DESCRIPTION

FIG. 1 is a left side elevational view of a multi-tool for fasteners showing my new design;

FIG. 2 is a right side elevational view thereof;

FIG. 3 is a front side elevational view thereof;

FIG. 4 is a rear side elevational view thereof;

FIG. 5 is a top plan view thereof;

FIG. 6 is a bottom plan view thereof; and,

FIG. 7 is a perspective view thereof.

Any elements shown in dotted and/or dashed lines are provided for illustrative purposes only and form no part of the design claimed. Any surface shading is used solely to show the character or contour of the surfaces represented.
